UNITED STATES PATENT OFFICE.

EDWIN P. CARPENTER, OF BRATTLEBOROUGH, VERMONT.

REED-ORGAN STOP-ACTION.

SPECIFICATION forming part of Letters Patent No. 328,647, dated October 20, 1885.

Application filed December 17, 1884. Serial No. 150,552. (No model.)

To all whom it may concern:

Be it known that I, EDWIN P. CARPENTER, a citizen of the United States, residing at Brattleborough, in the county of Windham and State 5 of Vermont, have invented certain new and useful Improvements in Organ-Actions; and I declare the following to be a description of my said invention sufficiently full, clear, and exact to enable others skilled in the art to 10 which it appertains to make and use the same, reference being had to the accompanying drawings, which form a part of this specification.

My present invention relates to the construction, location, and arrangement of the 15 operating-levers in connection with the back board of the brace, and to the expression-roll devices, in combination with the operating-levers, brace, and stop-pull mechanism, as more fully hereinafter explained, the particu- 20 lar subject-matter claimed being hereinafter definitely specified.

In the drawings, Figure 1 is a plan view showing so much of an organ-action as will 25 illustrate the nature of my invention. Fig. 2 is a vertical section on line $x-x$, drawn to a somewhat larger scale; and Fig. 3 is a view showing a section of the back board of the brace and the manner of combining the mute-operating levers therewith.

30 In referring to the drawings, A denotes the reed-board, B the key-frame, C the manual keys, and D the mutes, all of which parts may be of ordinary construction and arrangement.

35 E indicates the brace, and F the stop-pulls, arranged therein as shown, and provided with tumblers f, for depressing the ends of the mute-operating levers I when the pulls are drawn outward.

40 The back board or piece, E', of the brace is provided with a longitudinal groove or channel, e, extending along its lower front edge, in which groove the fulcrums or central portions of the wire levers I are supported and retained by suitable blocks or fastening devices, d, as illustrated. The upper or forward ends of the wire levers I are bent at right angles and arranged to extend transversely across the tumblers f, as at i, while their lower ends are 45 provided with coupling devices I', to which are detachably connected the wires J, that

work the mutes D, which latter are made to operate in the usual manner. Notches e' are formed at the lower edge of the back piece, E', for receiving the dependent portion of the levers I. By providing the back piece, E', of the brace with the groove e and arranging the fulcrums of the levers I directly in connection therewith, said piece E' is the only support required for both levers and stops, and thus a 55 very simple and easily-constructed mechanism is produced, while quite a saving is effected in the amount of stock and labor employed over that required by the ordinary manner of construction and arrangement. This construction of the back board or piece, E', and the fulcruming of the levers directly thereto is a feature of my invention.

50 K denotes the expression-roll, which I locate within the brace directly in rear of the name-board above the manual C and beneath the stop-pulls F. The ends of the roll K are journaled or supported in or upon the end pieces or transoms, E', of the brace, and said roll is provided with a backward-projecting 70 arm, L, or device for imparting a rocking action to the roll. Said arm L is connected by a link, m, to the cranked end m' of the rocker-rod M, which latter is connected to and operated by the knee-swell N in the usual manner, by the rod n. The roll K is provided with 75 a series of backward projections, arms, or pins, P, that extend over the transverse ends i of the operating-levers I, and by means of which the several levers I are simultaneously 80 depressed when said roll K is actuated by the knee-swell mechanism or other actuating devices.

85 By arranging the parts K and L as shown I am enabled to make the connections at m in 90 rear of the key-frame and without cutting through the manual, while a very simple, compact, and desirable mechanism is produced.

The expression-roll devices and lever device are made up in connection with the 95 brace in a manner that permits of their ready and convenient removal from the key-frame action to give access to the keys and key-frame, the brace being connected to the latter by hooks h and dowels a at either end, while the levers I and mute-links J are joined by a detachable lock at the joint I'.

What I claim as of my invention, and desire to secure by Letters Patent, is—

1. In an organ-action, the back piece, E', of the brace, provided with the groove e, in combination with the mute-operating levers I, fulcrumed and supported directly on said grooved back piece, substantially as hereinbefore set forth.
2. The combination, as described, of the brace E, having the grooved back piece, E' e, detachably secured to the key-frame B, the wire levers I, fulcrumed on said brace, the stop-pulls F, having mechanism for operating said levers, the mute D, and connecting-link J, detachably connected to said levers at I', substantially as shown and described.
3. The combination, substantially as here-

inbefore described, of the brace E, provided with the grooved back piece, E', the mute-operating levers I, fulcrumed thereon and provided with transversely offset top ends, i, the stop-pulls F, having a tumbler, f, for engaging and depressing said levers, the expression-roll K, mounted within the brace and having projections or pins P, for engaging the ends i 20 of said levers, and the arm L, connected with actuating devices, as in M, for the purposes set forth.

Witness my hand this 11th day of December, A. D. 1884.

EDWIN P. CARPENTER.
